AUTOMOBILE STONE SHIELD

Frederick Reynolds, Bloomfield Hills, Mich., assignor to Chrysler Corporation, Highland Park,
Mich., a corporation of Delaware

Application May 12, 1953, Serial No. 24,975

Term of patent 7 years

(Cl. D14—6)

To all whom it may concern:

Be it known that I, Frederick Reynolds, a citizen of the United States, residing in the city of Bloomfield Hills, county of Oakland, and State of Michigan, have invented a new, original, and ornamental Design for an Automobile Stone Shield, of which the following is a specification, reference being had to the accompanying drawing, forming part thereof, in which:

Fig. 1 is a side elevation of an automobile stone shield, showing my novel design; and

Figs. 2, 3 and 4 are sectional views taken on the lines 2—2, 3—3 and 4—4, respectively, of Fig. 1.

I claim:

The ornamental design for an automobile stone shield, substantially as shown.

FREDERICK REYNOLDS.
